DESIGN FOR A GAS RANGE

William T. Bradbury, Kankakee, Ill., assignor to
Florence Stove Company, Gardner, Mass., a
corporation of Massachusetts

Application August 27, 1934, Serial No. 53,087

Term of patent 7 years

To all whom it may concern:

Be it known that I, William T. Bradbury, a citizen of the United States, residing at Kankakee, in the county of Kankakee and State of Illinois, have invented a new, original, and ornamental Design for a Gas Range, of which the following is a specification, reference being had to the accompanying drawing, forming part thereof.

Figure 1 is a perspective view of a gas range showing my new design.

Fig. 2 is a perspective view of the upper portion of the range with the top covers in raised position to expose the cooking top grids.

I claim:

The ornamental design for a gas range substantially as shown.

WILLIAM T. BRADBURY.
